Attorney

By

UNITED STATES PATENT OFFICE.

CHARLES F. WILLINGHAM, OF DALLAS, TEXAS.

AUTOMATIC OVERFLOW ALARM.

Application filed March 10, 1922. Serial No. 542,726.

To all whom it may concern:

Be it known that I, CHARLES F. WILLINGHAM, a citizen of the United States, residing at Dallas, in the county of Dallas and 5 State of Texas, have invented certain new and useful Improvements in Automatic Overflow Alarms, of which the following is a specification.

This invention relates to improvements in 10 automatic alarms or signals and pertains particularly to an alarm device for use in connection with liquids contained in receptacles wherein a warning is desirable at a certain or approximate time.

15 The primary object of the invention is in the present instance to apply the principle and spirit thereof to the construction and arrangement of an automatic alarm for refrigerators and ice-boxes whereunder is 20 usually a basin or receptacle for collecting water from the melting ice, the object being to arrange the alarm by attachment to the basin or receptacle in such a manner as to cause a bell or alarm to sound when the 25 water has attained a certain height or accumulated to such an extent as to require removal before overflowing.

It is obvious that the device may also be 30 utilized for purposes other than in its application to a refrigerator or ice-box, for instance where a desired quantity of liquid is to be registered or measured and an alarm sounded when such amount is obtained, and it should be understood that the invention 35 is not limited to its present mode of application.

The invention will be more fully understood by reference to the following description, taken in connection with the accompanying drawings forming part hereof in 40 which—

Figure 1 is a fragmentary, broken view of a basin or receptacle for holding an accumulation of water from an ice box or refrigerator, and illustrating the device in 45 position thereupon.

Figures 2 and 3 are top or plan views of the device, the cover or bell being removed.

Figures 4 and 5 are vertical sectional 50 views of the alarm device with parts broken away, the views taken on lines 4—4 and 5—5, respectively, of Figure 2.

Figure 6 is a detail sectional view taken on line 6—6 of Figure 3.

55 Figure 7 is a perspective view of the

bracket for supporting the alarm device and for attaching it to the receptacle.

Figure 8 is a small pivoted plate or brake means; and

Figure 9 is a view of the device similar 60 to the view in Figure 3 illustrating the pivoted plate or brake means in position and holding the mechanism in locked position.

Referring more closely to the drawings, 1 65 denotes a receptacle for catching water dropping from the ice in an ice box or refrigerator, and 2 is a bracket with a set screw 2^a and a flange 3 for engagement in a slot 4 in a laterally extended tongue 4^a of a plate 5 for holding the alarm device in 70 position. The flange 3 forms an integral part of the bracket 2.

Secured to the plate 5 is a frame 6 with supporting downwardly bent portions or legs 7—7 secured to the plate 5 by screws as illustrated. This frame 6 has centrally positioned laterally extended arms 8—8, one of which, as depicted in Figure 3, provides a fastening means for one end of a spring 9, while the other arm, together with the spurs 10—10 in frame 6, serve to keep the spring in coiled formation. 11 is a ratchet wheel secured upon a shaft 12 seated in plate 5, and traversing a bearing 13 of the frame 6. The shaft 12 has a knurled nut 14 by means of which the shaft is rotated to contract the spring 9. A bell 15 is screwed to the bearing 13.

Referring to Figures 2, 3, 4 and 9, adjacent the ratchet wheel 11 is a pawl or dog 16 upon which is formed an annular member or ring 17 and pivoted with the ratchet to swing upon a pin 18.

The ring 17 is notched at 18^a and 19 for 90 engagement with a finger 20 of an upwardly projecting pin 21 secured to the cover 22^a of a float chamber 22. The cover of the float chamber is also provided with screws 23—23, the screws and pin 21 having free play in openings in plate 5 to permit the float chamber to move up and down upon pressure and gravity, the pin 21 and screws 23—23 maintaining the chamber in a centralized vertical position. The ring 17 has a downwardly projecting portion 17^a, leaving an annular space 17^b around the bottom of the ring for the lessening of friction upon the plate 5.

A clapper 24 is adapted, upon the lateral swing or side to side movement of the ring 17 to reciprocate within the slots 25—25 105 110

upon its ends 26-26, the ring oscillating between and against the upwardly projecting lugs 27-27. 28 denotes a plate pivoted to the plate 5 for the purpose of stopping the oscillatory movement of ring 17, acting as a brake.

In operation, water A in the receptacle 1, as it accumulates therein will, when the receptacle is sufficiently full, bear against the 10 float chamber 22 and rising upward will raise the chamber 22 and cause the finger 20 to move out of notch 19, whereupon the spring 9 will through ratchet 16 oscillate the ring from side to side, the clapper ends 15 26-26 striking against the bell 15. The clapper and ring will continue to operate until the pivoted plate or brake 28 is moved into the position shown in Figure 9. This latter movement of the brake will bring the 20 finger 20 of pin 21 over the notch 19 in the ring 17 so that when the float chamber 22 is again lowered and the brake released the pin will lock the ring against movement until water has again accumulated to bear against 25 the float chamber. The notch 18^a allows the finger 20 free play as the ring moves from side to side.

It will be noted by reference to Figure 1 that the alarm will sound in ample time to 30 permit the water to be removed from the basin or receptacle, and should this not be done the water will flow over the top of the receptacle without getting into the mechanism of the device.

35 It will be understood that various changes may be made in the construction and combination of the various elements illustrated and described in the above, without departing from the spirit of the invention, as announced in the appended claims.

40 What is claimed is—

1. In an overflow alarm, a casing, a bell carried by the casing, a pivoted ring-like member having a rigid pawl, a spring tensioned ratchet wheel having its teeth engageable with the pawl so as to oscillate the ring-like member, a clapper composed of a reciprocal member having its ends extended through opposite parts of the ring-like member to engage the bell, said ring-like member having a slot in its upper edge, a float, and a finger carried by the float and engageable in

the said slot to latch the ring-like member against oscillatory movement.

2. In an overflow alarm, a casing, a bell carried by the casing, a pivoted ring-like member, means to oscillate the member, a reciprocal member carried by the ring-like member and having its ends arranged to engage the bell, a float, and means carried by the float to engage the ring-like member and to latch the latter against oscillation.

3. In an overflow alarm, a casing, a bell carried by the casing, an oscillatory member, means to oscillate the member, a reciprocal member carried by the member and having its ends engaging the bell to sound the latter, a float, and means controlled by the float to normally hold the oscillatory member inactive and to release the latter upon predetermined movement of the float.

4. In an overflow alarm, a casing, a bell carried by the casing, an oscillatory member of open ring-like form, means to oscillate the member, a reciprocal member carried by the oscillatory member and having its ends engaging the bell to sound the latter, a float and means controlled by the float to engage on top of the oscillating member to normally hold the latter inactive and to release the oscillatory member upon predetermined movement of the float.

5. In an overflow alarm, a casing, a bell carried by the casing, an oscillatory member having an arcuate peripheral part, means to oscillate said member, bell sounding means carried by the member and operable by the oscillatory movements of the latter, manually controlled means engageable with the said peripheral part of the member to hold the latter against oscillation, and a float for controlling the oscillatory member.

6. In an overflow alarm, a casing, a bell carried by the casing, an oscillatory member, means to oscillate said member, a float for controlling the oscillatory member, and bell sounding means mounted on the member for longitudinal movement into and out of engagement with opposite sides of the bell to sound the latter, by and upon oscillatory movement of the member.

In testimony whereof I have signed my name to this specification.

CHARLES F. WILLINGHAM.
